(57) **CLAIM**

The ornamental design for a pattern for forming polygon, as shown and described herein.

DESCRIPTION

FIG. 1. Is a perspective view of our pattern for forming polygon in the unformed condition;

FIG. 2. Is a front view thereof;

FIG. 3. Is a top view thereof;

FIG. 4. Is a right side view thereof;

FIG. 5. Is a rear view thereof;

FIG. 6. Is a left side view thereof;

FIG. 7. Is a bottom view thereof; and,

FIG. 8. Is a view showing the pattern in the polygonal form.
